[57] CLAIM

The ornamental design for a mounting bracket, as shown and described.

DESCRIPTION

FIG. 1 is a front perspective view, viewed from beneath and to the left, of a mounting bracket showing my new design;

FIG. 2 is a rear perspective view of FIG. 1, taken from above and to the left;

FIG. 3 is a left end elevational view of FIG. 2;

FIG. 4 is a perspective view similar to FIG. 1 but with the hanger element omitted;

FIG. 5 is an enlarged front perspective view, taken from beneath and to the left, of the hanger element of FIG. 1;

FIG. 6 is an enlarged rear perspective view, taken from above and to the left, of the hanger element of FIG. 1;

FIG. 7 is a left side elevational view of FIG. 6; and

FIG. 8 is a top plan view of FIG. 6.

The side elevational views opposite to FIGS. 3 and 7 are mirror images thereof.

The design is for a mounting bracket, the main portion of which fits onto an object such as a brick, and including a separable hanger unit which, when mounted on the main portion includes an in-curving groove.
